UNITED STATES PATENT OFFICE.

WILLIAM F. HIRSCHMANN, OF NEW YORK, N. Y.

DESIGN FOR A STATUETTE.

47,189.

Specification for Design.

Patented Apr. 6, 1915.

Application filed January 21, 1915. Serial No. 3,644. Term of patent 14 years.

To all whom it may concern:

Be it known that I, WILLIAM F. HIRSCHMANN, a citizen of the United States, residing at New York, in the county of New York and State of New York, have invented a new, original, and ornamental Design for Statuettes; and I do hereby declare the following to be a full, clear, and exact description of the invention, such as will enable others skilled in the art to which it appertains to make and use the same.

In the drawings, the figure is a perspective view of a statuette embodying my new design.

I claim:

The ornamental design for a statuette, substantially as shown.

In testimony whereof I have signed my name to this specification in the presence of two subscribing witnesses.

WILLIAM F. HIRSCHMANN.
